COMBINATION HIBACHI TABLE AND HOOD

James T. Sakata, 1020 Kearny St.,
San Francisco, Calif. 94111

Filed May 26, 1966, Ser. No. 2,443

Term of patent 14 years

(Cl. D81—10)

The drawing is a perspective of a combination hibachi table and hood embodying my new design.

The right side is a mirror image of the left side and the rear, not shown, is flat, vertical and plain.

I claim:

The ornamental design for a combination hibachi table and hood, substantially as shown and described.
